INVENTOR
WALTER P. DORL.
BY
Ralphson A. Parker
HIS ATTORNEY.

UNITED STATES PATENT OFFICE.

WALTER P. DORL, OF DETROIT, MICHIGAN.

DOOR-CONTROLLING APPARATUS.

1,338,073.

Specification of Letters Patent. Patented Apr. 27, 1920.

Application filed February 26, 1919. Serial No. 279,244.

To all whom it may concern:

Be it known that I, WALTER P. DORL, a citizen of the United States, residing at Detroit, county of Wayne, State of Michigan, have invented a certain new and useful 5 Improvement in Door-Controlling Apparatus, and declare the following to be a full, clear, and exact description of the same, such as will enable others skilled in the art to which it pertains to make and use the same, reference being had to the accompanying drawings, which form a part of this specification.

My invention relates to door closing apparatus for automobiles and an object of my improvements is to provide an improved device for door checks of an automobile which may be cheaply constructed, easily applied and when so applied will be concealed from view, hold the door open in one position and automatically close the door on a slight movement.

I secure this object in the device illustrated in the accompanying drawings in which;

Figure 1 represents the body frame of an automobile illustrating the application thereto of the apparatus embodying my invention.

Fig. 2 is a section on the broken line 2—2 Fig. 3.

Fig. 3 is a plan view of the casing, the horizontal portion of the cover being cut away and removed.

Fig. 4 is a section on the line 4—4 Fig. 3.

Fig. 5 is a section on the line 5—5 Fig. 3.

Fig. 6 is a detail perspective view of one of the holding parts.

Fig. 7 is a perspective view of the cross-head or yoke.

Fig. 8 is a representation of the mechanism for holding the door open.

a is the body frame and *b* designates the doors. The apparatus embodying my invention is secured either to the frame or to the door as will be obvious without special explanation to those skilled in the art. In either case the strap *j* is secured at a point *j*² to the other part from that to which the casing *c* is secured. The opening of the door draws the strap *j* out of the casing which motion is resiliently resisted by springs within the casing and said springs act to retract the strap and close the door.

55 The casing *c* is made up of a portion hav-

ing the bottom *c*², and the upwardly extending rear end *c*⁵, its front end being open, except for the lugs *c*^{3a} formed by the upturned edges of the bottom *c*² of the first mentioned part.

There are guide rods *d* *d* in the casing *c* extending longitudinally thereof and parallel to each other, one of said rods being adjacent to each of the casing sides. There is a yoke, or cross-head, *f* having lugs *f*² *f*² at each end which lugs are provided with apertures *f*⁵ fitting over the rods *d* and adapted to slide thereon. The yoke *f* is bent at right angles in two parallel portions a short distance from its ends, the outer end of these portions being joined by the integral bar *f*³. *d*² *d*² are springs threaded upon the rods and acting to force the yoke *f* to its innermost position. A strap *j* is looped around the bar *f*³ to secure it to the yoke *f* and extends along the casing and out at the open end of the same, the end of said strap being secured by screws *j*³. *e*^{3a} *e*^{3a} are two U-shaped pieces adapted to fit against the lugs *c*^{3a} with the ends of their branches resting against said lugs. Each of said lugs is provided with an aperture *c*⁴ in which one end of the rod *d* engages, the other end of said rod passes through an aperture in the upturned end *c*⁵ of the bottom of the casing *c*. Each of the U-pieces *e*^{3a} is provided with an aperture *e*² in which a rod *h*' engages, the ends of said rods being adjacent to the sides of the casing. *h* is a sleeve upon the rod *h*' between the two U-pieces *e*^{3a} *e*^{3a} and forming a friction roller over which the strap *j* passes.

The casing is secured to the frame-work by screws *c*⁹ through stop blocks *c*⁸ and through the bottom *c*². In various positions in the line of travel of the yoke *f* apertures *c*^{8a} are formed vertically through the bottom of the casing *c* and screws or bolts *c*^b engage through these apertures. These bolts may be placed in any of these apertures and serve to limit the motion of the yoke *f*.

In Fig. 8 I have shown a means for holding the door open in connection with the strap *j*. The roller *h* is shown in section and is shown in this figure distinct from the other and supporting apparatus. Attached to the strap *j* by riveting is a lug *j*' arranged in such position on the strap *j* that when the door approaches or reaches the position at

right angles to the body of the car the lug j' is drawn over the roller h and assumes the position shown in Fig. 8. This lug holds the strap j from being retracted by the 5 spring so long as the door is in the position substantially as shown in Fig. 1. A slight movement of the door inward would release the lug from the roller h and allow the roller to pass over the tip j^2 and the spring to act 10 in the manner hereinbefore described to close the door.

The method of assembling and using the above described apparatus is as follows:

The yoke f being threaded upon the rods 15 d and the springs d^2 placed thereon, a part e^{3a} being placed upon each of the rods d a spring d^2 engaging a part e^{3a} and against a lug f^2 of the yoke f . The rod h' is inserted 20 in place, the ends of the rods d are passed through the apertures in the ends c^5 of the casing c and the parts e^{3a} are placed within the casing engaging against the lugs c^{3a} which are turned up from the bottom c^2 of 25 the casing so as to hold the parts e firmly in place. The casing is then secured, say, to the frame of the machine adjacent to the hinged edge of the door and the outer end

of the strap j is secured to the door. Now, when the door is opened the strap j will be drawn outward carrying the yoke f along 30 with it against the action of the springs d^2 and when the door is released said springs will force the yoke f back to its inner position drawing the door to its closed position.

The casing is covered by the body lining 35 as indicated in Fig. 1 at z .

What I claim is:

In an apparatus of the kind described, the combination of a door, a jamb to which said door is pivotally attached, a flexible 40 strap attached to said door at one end of said strap, resilient means secured to said jamb and operating by said strap to close the door, a friction roller over which said strap passes when the door is opened, means 45 on said strap adapted to engage said roller and prevent the retraction of said strap and closing of said door when said door is at an angle with the jamb said engaging means being adapted to be released from said roller permitting said door to be closed. 50

In testimony whereof, I sign this specification.

WALTER P. DORL.
